UNITED STATES PATENT OFFICE.

WILLIAM J. CHAMBERS, OF CHICAGO, ILLINOIS, ASSIGNOR TO AMERICAN CAN COMPANY, OF NEW YORK, N. Y., A CORPORATION OF NEW JERSEY.

SHEET-METAL POCKET TOBACCO-BOX.

No. 889,904.

Specification of Letters Patent.

Patented June 9, 1908.

Application filed July 12, 1907. Serial No. 383,375.

To all whom it may concern:

Be it known that I, WILLIAM J. CHAMBERS, a citizen of the United States, residing in Chicago, in the county of Cook and State 5 of Illinois, have invented a new and useful Improvement in Sheet-Metal Pocket Tobacco-Boxes, of which the following is a specification.

My invention relates to improvements in 10 sheet metal receptacles, and more particularly to the construction of pocket boxes for tobacco and other articles.

My invention consists in a sheet metal box 15 having a body of suitable size and shape for carrying in the pocket, and provided with countersunk heads double seamed to the body to give the same round smooth corners, free from sharp edges or angles, the countersunk portion of the top head having a pouring 20 opening therein at one end, and furnished with a depressed channel and a transverse slot to receive the shank of a closure slide, and also inwardly projecting integral lips or guides for holding and guiding the slide in 25 place, and a closure slide fitting on the inner side of the top head and having its shank projecting through the transverse slot there- 30 in to enable the slide to be conveniently opened and closed; the slide being removable from or applicable to the countersunk head before the head is seamed to the body, by simply slipping its wider portion towards one end until the same clears the guide lips, and said inside fitting closure slide being ir- 35 removable from the top head after said head has once been seamed to the body, so that the seam uniting the head to the body cooperates to prevent the removal of the closure slide.

40 My invention further consists in the novel construction of parts and devices and in the novel combinations of parts and devices herein shown and described.

In the accompanying drawing, forming a 45 part of this specification Figure 1 is a top or plan view of a sheet metal pocket tobacco box embodying my invention. Fig. 2 is a vertical transverse section on line 2—2 of Fig. 1. Fig. 3 is a longitudinal vertical section on line 3—3 of Fig. 1. Fig. 4 is a horizontal section on line 4—4 of Fig. 3. Fig. 5 is a detail plan view of the closure slide, and Fig. 6 is a detail bottom plan view of the top head of the box and closure slide before the

head is seamed to the body, the closure slide 55 being shown drawn out so that the wider portion of the closure slide will clear the guide lips on the top head.

In the drawing A represents the sheet metal body of the box, having an internally 60 projecting lock side seam a , so that the exterior surface of the box body will be smooth and free from ribs or projections. The box body has an inner upright flat side a^1 , an outer curved wall a^2 and rounded or curved 65 end walls a^3 a^3 to give the body of the box a wide narrow shape suitable for fitting in the hip or other pocket.

B is the countersunk top head of the box, and C the similarly countersunk bottom 70 head. The countersunk top head B has a countersink wall or upright flange b fitting snugly within the upper end of the body A, and is secured thereto by a double or other folded seam a^4 . And the bottom head C has 75 a similar countersink wall c , and is likewise secured to the body A at its lower end by an externally folded double seam a^5 , thus providing the box with smooth round corners at both ends, free from any sharp edges or 80 angles.

The countersunk top head B has at one end of its countersunk portion C' pouring openings B^1 , surrounded at the sides and curved end by a horizontal ledge or flange b^2 85 to serve as a flat face or bearing for the marginal portion of the closure slide D, which fits and reciprocates on the inside of the countersunk top head B. The central flat portion b^1 of the top head B is provided with 90 a longitudinal depression b^3 to receive the shank portion d of the closure slide, which projects through the transverse slot b^4 in the top head B. The top head B is further provided with two inwardly projecting integral 95 guide lips b^5 b^6 , one on each side of the closure slide D, and located adjacent to the inner end of the pouring opening B^1 , so that when the slide D is moved to the limit of its opening movement the guide lips b^5 will still properly engage and hold in place the closure slide, and so that when the slide is moved in the opposite direction the wider portion of the closure slide will clear said lips and thus permit said slide to be readily removed from the 100 top head or applied thereto before such head is secured to the body of the box, as will be readily understood from Fig. 6 of the draw-

ing, which is a bottom view of the top-head of the box and closure slide before said top-head is seamed to the box body.

The closure slide holding and guiding lips 5 b^6 preferably project flush with the countersunk wall b of the top head, and the width of the closure slide preferably substantially equals the width of the countersunk portion of the top head, so that the upright walls of 10 the box body will serve as further guides to the marginal edges of the closure slide.

The shank d of the closure slide which projects through the transverse slot b^4 in the top head B , is provided with a transverse roll, 15 fold, shoulder, or thumb piece d^1 for convenience in opening and closing the slide with the thumb or finger. The transverse slot b^4 in the top head is made wide enough to receive the roll or folded end d^1 of the closure 20 slide.

In operation the closure slide is first applied to the top head in the manner indicated by Fig. 6, and before the top head is seamed to the body, and then the top head is seamed 25 to the body of the box, after which the slide is irremovable without destroying the box, as the guide and holding lips for the closure slide are upon the inside of the top head, and consequently cannot be got at to unclench them or bend them outward. The box is 30 filled with tobacco before last one of the two heads B or C is seamed to the body. And as the pouring opening is comparatively small, so that the box cannot be practically or conveniently 35 filled with tobacco through the pouring opening, it will be understood that my improved box is of a practically non-refillable construction, and is, therefore, specially adapted for use as a tobacco package, 40 requiring application and cancellation of revenue stamps at the tobacco factory.

I claim:

1. A sheet metal pocket box having a thin wide body with curved walls a^3 at its 45 upper edges, and countersunk top and bottom heads fitting within the ends of the body and irremovably seamed thereto, said top head being provided with a pouring opening at one end thereof and a transverse slot at its 50 middle portion, and a closure slide on the inside of said top having a shank projecting through a transverse slot in the top head, said top head having inwardly projecting lips engaging said slide for holding and guiding 55 the same, substantially as specified.

2. A sheet metal pocket box having a thin wide body with curved walls a^3 at its upper edges, and countersunk top and bottom heads fitting within the ends of the body and 60 irremovably seamed thereto, said top head being provided with a pouring opening at one end thereof and a transverse slot at its middle portion, and a closure slide on the inside of said top having a shank projecting 65 through a transverse slot in the top head,

said top head having inwardly projecting lips engaging said slide for holding and guiding the same, said top head being also provided with a longitudinally extending channel or depression to receive the shank of the 70 closure slide, substantially as specified.

3. A sheet metal pocket box having a thin wide body with curved walls a^3 at its upright edges, and countersunk top and bottom heads fitting within the ends of the body and irremovably seamed thereto, said top head being 75 provided with a pouring opening at one end thereof and a transverse slot at its middle portion, and a closure slide on the inside of said top having a shank projecting through 80 a transverse slot in the top head, said top head having inwardly projecting lips engaging said slide for holding and guiding the same, said top head being also provided with a longitudinally extending channel or depression 85 to receive the shank of the closure slide, and the shank of the closure slide having a curved flange at its end, substantially as specified.

4. In a sheet metal box, the combination 90 with the body, a head seamed thereto and furnished with a pouring opening at one end thereof and a transverse slot at its middle portion, of a closure slide fitting on the inside of said head and having a shank projecting 95 through said transverse slot in said head, said closure slide being applicable to said head before the head is seamed to the body and irremovable therefrom after the head is seamed to the body, substantially as specified. 100

5. In a sheet metal box, the combination with the body, a head seamed thereto and furnished with a pouring opening at one end thereof and a transverse slot at its middle portion, of a closure slide fitting on the inside of said head and having a shank projecting through said transverse slot in said head, said closure slide being applicable to said head before the head is seamed to the body and irremovable therefrom after the head is seamed to the body, and integral guide lips on the inside of said head for said slide, substantially as specified. 110

6. In a sheet metal box, the combination with the body, a head seamed thereto and furnished with a pouring opening at one end thereof and a transverse slot at its middle portion, of a closure slide fitting on the inside of said head and having a shank projecting through said transverse slot in said head, said closure slide being applicable to said head before the head is seamed to the body and irremovable therefrom after the head is seamed to the body, and integral guide lips on the inside of said head for said slide, said head having a longitudinal channel or depression to receive and guide the shank of said slide, substantially as specified. 120

7. A sheet metal pocket tobacco box, having a flat back wall, a curved front wall and 130

- curved edge walls, and provided with countersunk heads irremovably seamed to the ends of said body one of said heads having a pouring opening at one end thereof and a 5 transverse slot at its middle portion and provided with inwardly projecting guide lips adjacent to said pouring opening, and a long longitudinally reciprocating slide extending through said transverse slot and fitting 10 partly inside and partly outside said head, said slide being wider at its inside fitting portion than at its outside fitting portion, substantially as specified.
8. A sheet metal pocket tobacco box, having a flat back wall, a curved front wall and curved edge walls, and provided with countersunk heads irremovably seamed to the ends of said body, one of said heads having a small pouring opening at one end thereof and 15 a transverse slot at its middle portion and a slide for closing it, said slide having a wide portion fitting inside said head, and a narrow portion fitting outside said head substantially as specified.
- 20 9. In a sheet metal box, the combination with a top head having a pouring opening at one end thereof and a transverse slot at its middle portion, of a closure slide on the inside of said top head having a shank projecting through said transverse slot in said head, and 25 a transverse slot at its middle portion and a slide for closing it, said slide having a wide portion fitting inside said head, and a narrow portion fitting outside said head substantially as specified.
- 30

said head having integral inwardly projecting lips engaging said slide for guiding and holding the same, substantially as specified.

10. In a sheet metal box, the combination with a top head having a pouring opening at 35 one end thereof and a transverse slot at its middle portion, of a closure slide on the inside of said top head having a shank projecting through said transverse slot in said head, said head having integral inwardly projecting 40 lips engaging said slide for guiding and holding the same, said head being also furnished with a longitudinal channel to receive said shank, substantially as specified.

11. In a sheet metal box, the combination 45 with a top head having a pouring opening at one end thereof and a transverse slot at its middle portion, of a closure slide on the inside of said top head having a shank projecting through said transverse slot in said head, 50 said head having integral inwardly projecting lips engaging said slide for guiding and holding the same, and said shank having a curved flange at its end, substantially as specified.
